UNITED STATES PATENT OFFICE.

DAVID H. MOSS, OF NEWARK, NEW JERSEY, ASSIGNOR TO BRANDES LABORATORIES, INC., OF NEWARK, NEW JERSEY, A CORPORATION OF NEW JERSEY.

PHONOGRAPH ATTACHMENT.

Application filed January 8, 1926. Serial No. 80,120.

My invention relates broadly to electromagnetic sound reproducers and more particularly to an electromagnetic sound reproducing attachment for phonographs.

5 One of the objects of my invention is to provide a construction of electromagnetic sound reproducer for phonographs which may be readily manufactured inexpensively on a quantity production basis to provide 10 a simple device which may be connected in the output circuit of any radio receiver and connected with the tone arm of a phonograph for utilization of the sound amplifying horn of the phonograph as a reproducer 15 of the received signaling energy.

Another object of my invention is to provide a construction of phonograph attachment for the reproduction of radio concerts, lectures, news, music and other entertainment in which an electromagnetic sound reproducing mechanism may be adjusted with respect to the sound reproducing diaphragm to a point of desired amplitude and tone 20 quality, with means for limiting the movement of the electromagnetic sound reproducing mechanism in the direction of the sound reproducing diaphragm for preventing undue strain being placed upon the sound reproducing diaphragm by abutment of the 25 sound reproducing magnets with the surface of the diaphragm.

Still another object of my invention is to provide a construction of casing for a phonograph attachment where a portion of the 30 casing is struck to cooperate with an adjustable lever secured to the electromagnetic driving mechanism for limiting the movement of the electromagnetic driving mechanism with respect to the sound reproducing 35 diaphragm for preventing abutment of the electromagnets with the diaphragm.

A further object of my invention is to provide a mounting for an electromagnetic driving mechanism in which the electromagnetic 40 pole pieces are carried upon a screw threaded plate member which may be rotatably adjusted within a casing which supports the sound reproducing diaphragm with means for actuating the electromagnetic 45 driver from a point exterior to the casing for varying the distance between the electromagnets and the sound reproducing diaphragm from a minimum determined by a limiting stop between the electromagnetic 50 driver and a projection from one wall of the

phonograph attachment casing to a maximum which is substantially 360° in the reverse direction from the limiting position.

My invention will be more clearly understood from the specification hereinafter following by reference to the accompanying drawings, wherein:

Figure 1 is a partial perspective view showing the relative position of a phonograph attachment construction in accordance with my invention mounted upon a phonograph; Fig. 2 is an end view of the phonograph attachment casing; Fig. 3 is a plan view showing the phonograph attachment casing and a connecting nozzle which interconnects the tone arm of a phonograph with the phonograph attachment casing; Fig. 4 is a cross-sectional view through the phonograph attachment casing showing the interior working parts in front elevation; 75 and Fig. 5 is a cross-sectional view through the phonograph attachment on line 5-5 of Fig. 4.

Referring to the drawings in detail, the phonograph attachment has been illustrated 80 as having a casing 1 with an extended cylindrical portion 2 forming a sound delivery orifice for the attachment. An end wall of the casing 1 is provided on its interior with an annular projecting ring member 3 forming a support for a sound reproducing diaphragm which is gripped upon its opposite side by a screw-threaded ring member 5 having an annular projecting ring portion 6 which grips the surface of the sound reproducing diaphragm. The casing 1 is threaded interiorly as represented at 7 to receive a screw threaded plate member 11 having a screw threaded portion 9 which is engaged with the screw threads 7 for adjustably positioning the electromagnet 7 with respect to the diaphragm 4. The periphery of the plate member 11 is toothed as represented at 10 in order to provide for an adjustment of the electromagnetic driving mechanism from the exterior of the casing. A gasket member 8 is positioned between the upper surface of the screw threaded portion 9 and the screw threaded ring member 5 enabling the electromagnet 12 to be adjusted 105 with respect to the sound reproducing diaphragm and all of the parts locked in position against mechanical vibration and rattling. In the center of the plate member 11 I provide a projecting screw member 14 su 110

rounded by a central serrated portion 16 around which a lever member 15 may be adjusted. The lever member 15 projects radially from the central screw member 14 and is bent at right angles as represented at 5 17 to present an end portion 18 which clears the binding posts 33 which connect with the bobbins 12. The lever member 15 may be adjusted in any desired angular position and 10 set in such position by tightening the screw member 14. Casing 1 is provided with an extension 30 which forms a bearing for a shaft member 31 which projects outside of the closure of the phonograph attachment. 15 The shaft member 31 carries a pinion 32 which meshes with the toothed periphery 10 of the plate 11 enabling the plate 11 to be adjusted in the screw threads 7 of casing 1 to present the magnets 12 at a desired position 20 with respect to diaphragm 4. The shaft 31 projects outside of the phonograph attachment casing and is operated by a knob member 34. The casing comprises a curved wall 24 terminating in portions 22 and 23 and 25 provided with a bottom closure portion 20. The rear wall 25 entirely encloses the electromagnetic driving mechanism carried by casing 1 and has an outlet 35 therein through which the flexible conductors 36 pass to the 30 output terminals of the electron tube amplifier of the radio receiver. The bottom wall 29 of the phonograph attachment casing is 35 struck as represented at 19 leaving a gap 21 therein and providing an obstruction member for path of movement of the end 18 of the radial adjustable lever 15. The 40 struck portion 19 extends vertically upwardly and forms an abutment for the end 18 of the lever 15 when the knob 34 is rotated to move the plate member 11 to a position where the pole pieces of the magnet bobbins 12 tend to abut with the surface of diaphragm 4. This construction provides a 45 limiting stop feature for the electromagnetic driver to prevent excessive strain from being placed upon the diaphragm 4 by continued movement of the magnet bobbins 12 thereagainst. A magnetic reluctance gap is 50 formed between the ends of the pole pieces of the magnet bobbins 12 and the diaphragm 4 for securing a desired operation of the phonograph attachment and the screw member 14 then adjusted to position the lever 15 in abutment with the upwardly extending 55 lug member 19 preventing a further decrease in the magnetic reluctance gap. With this setting of the device by factory inspection the attachment is capable of adjustment 60 through an angular movement of substantially 360° upon rotation of knob 34 to secure a desired operation of the attachment with respect to amplitude and tone quality for a given characteristic of the incoming 65 signaling energy. The seat portions 22 and 23 permit the attachment to be mounted conveniently adjacent the record table of a phonograph as illustrated in Fig. 1 where the tone arm 27 of the phonograph 28 is connected through a link 26 with the sound delivery orifice 2 of the casing 1 and connection established by means of the rubber nozzle 25. The attachment is mounted adjacent the record table 29 of the phonograph and no modification is necessary with the exception of the removal of the phonograph 70 sound box from the tone arm and the substitution of the connector 25 thereon. 75

The construction of the phonograph attachment is substantially fool-proof by reason of the limiting stop adjustment which I provide which prevents careless operation of the adjustable knob 34 and the ultimate destruction of the sound reproducing diaphragm. The adjustable magnetic reluctance gap affords means for securing a high 80 degree of efficiency in the reception of signaling energy of differing characteristics. 85

While I have described the attachment in certain specific embodiments, I desire that it be understood that modifications may be 90 made and that no limitations upon the invention are intended other than those imposed by the scope of the appended claims. 95

What I claim and desire to secure by Letters Patent of the United States is as follows:

1. A phonograph attachment comprising in combination an electromagnetic driving mechanism, a casing into which said mechanism may be screw threaded, a diaphragm carried in said casing, a closure covering the rear of said casing and engaging the sides thereof, means passing through said closure for controlling the rotation of said driving mechanism within said casing for effecting an adjustment of said driving mechanism with respect to said sound reproducing diaphragm, and means projecting from one side of said closure adjacent the rear of said electromagnetic driving mechanism for preventing decrease in the magnetic reluctance gap between said electromagnetic driving mechanism and said diaphragm beyond a selected limiting distance. 105
2. A phonograph attachment comprising in combination an interiorly screw threaded casing, a sound delivery orifice extending from one side thereof, a sound reproducing diaphragm carried within said casing, a plate member screw threaded within said casing, an electromagnetic driving mechanism carried by said plate member and adjusted with respect to said diaphragm for varying the magnetic reluctance gap therebetween, a closure arranged to be telescoped over said casing and substantially conforming with the shape thereof, rotary means for imparting rotary movement to said plate member, an integral tongue projecting from the inner walls of said closure and a cooper- 110 115 120 125 130

ating tongue extending from said plate member, said last mentioned tongue being angularly adjustable on said plate member for fixing the limit of movement of said electromagnetic driving mechanism with respect to said diaphragm.

3. A phonograph attachment comprising in combination an interiorly screw threaded casing, a sound delivery orifice extending 10 from one side thereof, a sound reproducing diaphragm carried within said casing, a plate member screw threaded within said casing, teeth formed on the periphery of said plate member, an electromagnetic driving mechanism carried by said plate member, a shaft member journaled in said casing and having a pinion thereon for engagement with the teeth on the periphery of said plate, a closure telescoped upon said casing 20 and substantially conforming with the shape thereof, said shaft member projecting through said closure and rotatable from the exterior thereof within predetermined limits for varying the magnetic reluctance gap between 25 said electromagnetic driving mechanism and said diaphragm.

4. A phonograph attachment comprising in combination an interiorly screw threaded casing, a sound delivery orifice extending 30 from one side thereof, a sound reproducing diaphragm carried within said casing, a plate member screw threaded within said casing, a lever member mounted upon a stud centrally projecting from one side of 35 said plate member, an electromagnetic driving mechanism carried by the opposite side of said plate member, a closure telescoped

over said casing, a rotatable shaft member journaled in said casing and passing through said closure for adjusting the position of 40 said plate member in said casing, said closure having an instruck projection forming an abutment with the end of said lever member for providing a limiting stop to the movement of said electromagnetic driving 45 mechanism beyond a selected magnetic reluctance gap.

5. A phonograph attachment comprising in combination an interiorly screw threaded casing, a sound delivery orifice extending 50 from one side of said casing, a sound reproducing diaphragm positioned within said casing, a plate member screw threaded within said casing and carrying electromagnetic driving mechanism for actuating said sound 55 reproducing diaphragm, a lever member mounted upon the stud projecting from the rear of said plate member, a substantially triangular shaped casing telescopically positioned upon said first mentioned casing, said 60 triangular shaped casing providing a support for said first mentioned casing and having an inwardly projecting lug member therein arranged to form an abutment for the end of said lever member for providing 65 a limiting stop to the movement of said electromagnetic driving mechanism beyond a predetermined position for fixing the minimum and maximum magnetic gap to which 70 said driving mechanism may be adjusted with respect to said sound reproducing diaphragm.

In testimony whereof I affix my signature.
DAVID H. MOSS.
